UNITED STATES PATENT OFFICE.

JOSEPH BERTRAM DE HART, OF LETHBRIDGE, ALBERTA, CANADA.

SHOT-FIRING DEVICE.

Application filed July 30, 1924. Serial No. 729,108.

To all whom it may concern:

Be it known that I, JOSEPH BERTRAM DE HART, a subject of the King of Great Britain, and a resident of the city of Lethbridge, in the Province of Alberta, Canada, have invented certain new and useful Improvements in Shot-Firing Devices, of which the following is a specification.

My invention relates to improvements in shot firing devices, the objects of which are to provide means whereby an electrical connection may be safely made to ignition batteries when shot firing in mines and other situations where inflammable gas is likely to be encountered.

The invention consists essentially of a tubular body adapted to be connected to any ignition battery in which the conductor wires from the battery are disposed, and a plug adapted for connection to the shot igniter, which is provided with terminals which form a contact with the leads within the tubular body, as will be more fully described in the following specification, in which:—

Fig. 1 is a sectional view of my invention showing the top of the battery to which it is fitted.

Fig. 2 is a plan view looking down.

In the drawings like characters of reference indicate corresponding parts in each figure.

The numeral 1 indicates a battery of any suitable type having binding posts 2 and 3 respectively. 4 is a hinged cover to the battery to which the tubular body 5 is attached by a pair of lugs 6. The body 5 is provided with a lower parallel bore 7 and an upper parallel bore 8 which is threaded at its upper end as at 9. In the upper bore 8 an insulating sleeve 10 is fitted which is adapted to seat upon an insulating washer 11, and bearing down upon the sleeve 10 is a screw cap 12 having a plurality of air vents 13 therein. Within the cap a pair of gauze discs 14 are fitted which are spaced apart by a collar 15 and are supported from the sleeve 10 by a further collar 16. The upper portion of the lower bore 7 is provided with an insulating sleeve 17.

The numeral 18 indicates a contact sleeve which is recessed and threaded as at 19 for the purpose of holding the inner contact sleeve 20 in position. The numeral 20 indicates the inner contact sleeve provided with an external flange 21 disposed within

the threaded recess 19 of the contact sleeve 18 and is insulated therefrom by a pair of insulating washers 22, the sleeve 20 being held in position by an externally threaded collar 23.

The numeral 24 indicates a wire from which the electrical current is led from the binding post 3 of the battery. The numeral 25 indicates a wire from which the current is led from the binding post 2 of the battery to the inner contact sleeve 20, through a screw plug 26 which is screwed into the inner sleeve and is tightened up against an insulating collar 27. The screw plug 26 is provided with a central orifice 28 for the purpose of permitting the free escape of air or gas from the tubular body 5 as the connector rod 31 is inserted.

The numeral 29 indicates a contact plunger slidably within the inner contact sleeve 20 which is downwardly pressed by a spring 30. The numeral 31 indicates a connector rod which is preferably formed with a tube 32 having an external diameter substantially equal to the lower bore 7 of the tubular body 5 and which is provided with a plug 33 of non-conducting material reduced at its upper end and provided with an inwardly flanged collar 34 of a diameter equal to that of the recess 35 of the outer contact sleeve 18 so that as the connector rod and its collar 34 are pushed upwards into place, the air contained within the lower portion of the body is forced upwards through the orifice 28 of the screw cap 26.

The numeral 36 indicates a cap covering the lower end of the tube 32, having connector plugs 37 and 38 respectively disposed therein, to which wires 39 leading to the firing charge are connected by connector screws 40. A wire is led from the connector plug 38 to the contact collars 34 and a further wire is led from the plug 39 through the axis of the plug 33 terminating in a button 41 which forms a contact with the contact plunger 29.

Having thus described the several parts of my invention I will briefly explain its operation.

When the wires 39 leading from the charge are connected to the connector plugs 37 and 38 it suffices to thrust the rod 31 upwards into the tubular body 5 forcing the air upwards to discharge through the gauze discs 14 and the air vents 13, prior to the electrical contact being made between the contact

collar 34 and the contact sleeve 18 and between the button 41 and the contact plunger 29.

Should the atmosphere in which the device is used be impregnated with combustible gas and a spark be produced at the contact points when the electrical circuit is closed, the flame produced by the ignition of the gas will be confined within the tubular body and the resulting expansion taking place upwards through the gauzes 14 which will prevent the passage of the flame, and any flame striking downwards within the confined annular space between the rod 31 and the walls of the body 5 will be spent and cooled before reaching the lower extremity of the bore 7.

What I claim as my invention is:

1. A shot firing device comprising a tubular member, a pair of contacts mounted in the tubular member and insulated therefrom and from each other, a nonconducting contact bearing member carrying contacts adapted to successively engage the contacts of the tubular member as they are thrust one within the other, and shot firing wires connected to the contacts of the contact bearing member.
2. A shot firing device comprising a tubular member, a pair of contacts mounted in the tubular member and insulated therefrom and from each other, a nonconducting contact bearing member carrying contacts adapted to successively engage the contacts of the tubular member as they are thrust one within the other, and shot firing wires connected to the contacts of the contact bearing member, and means for preventing outward flashing as the contacts engage.
3. A shot firing device comprising a tubular body having a screened and vented upper chamber and an open ended lower chamber, a pair of electrical contacts carried in the lower chamber and adapted for connection to an ignition battery, a connector rod of substantially similar diameter to the lower chamber adapted for insertion into the lower chamber and having electrical contacts corresponding to those in the lower chamber, and means for connecting a pair of shot firing wires to the connector.
4. A shot firing device comprising a tubular body having a screened and vented upper chamber and an open ended lower chamber

ber, a pair of electrical contacts carried in the lower chamber and adapted for connection to an ignition battery, a connector rod of substantially similar diameter to the lower chamber adapted for insertion into the lower chamber and having electrical contacts corresponding to those in the lower chamber, means for connecting a pair of shot firing wires to the connector, and means for discharging the air normally residing in the lower chamber through the vented upper chamber as the connector rod is thrust into the tubular body.

5. A shot firing device comprising a tubular body having an open ended lower chamber, a pair of electrical contacts carried in the lower chamber and adapted for connection to an ignition battery, a connector rod of substantially similar diameter to the lower chamber adapted for insertion into the lower chamber, a pair of electrical contacts corresponding to those in the lower chamber, means for connecting a pair of shot firing wires to the connector contacts, means for forming connection between one contact in the lower chamber and the corresponding contact of the rod when the rod is partially thrust into the tubular body, and for forming a yielding connection between the remaining pair of contacts as the rod is thrust to its ultimate position within the hollow body.

6. A shot firing device comprising a tubular body adapted for attachment to an ignition battery, a screened upper chamber and an open ended lower chamber to the body, insulated contacts adapted for connection from the battery disposed within the lower chamber, an air communication between the lower chamber and the upper chamber, a connector rod adapted for sliding movement within the lower chamber and having electrical contacts at one end for engaging the first named contacts when the rod is thrust into the hollow body, and means at the opposite end of the rod for connection to a pair of shot firing wires.

Dated at Lethbridge, Alberta, this 17th day of July, 1924.

JOSEPH BERTRAM DE HART.
